US00D648512S

(12) **United States Design Patent**
Schlageter et al.

(10) **Patent No.:** **US D648,512 S**
(45) **Date of Patent:** **** Nov. 15, 2011**

(54) **FOOTWEAR**

(75) Inventors: **David Schlageter**, Mequon, WI (US);
Marvin Z. Arnold, West Palm Beach, FL (US)

(73) Assignee: **Davmar, Inc.**, Mequon, WI (US)

(**) Term: **14 Years**

(21) Appl. No.: **29/367,455**

(22) Filed: **Aug. 9, 2010**

(51) **LOC (9) Cl.** **02-04**

(52) **U.S. Cl.** **D2/923; D2/896; D2/926**

(58) **Field of Classification Search** D2/896,
D2/900, 902, 903, 923-926, 969; 36/1, 83-95,
36/102, 104, 112-114, 11, 45, 58.5, 58.6

See application file for complete search history.

(57) **CLAIM**

An ornamental design for footwear, as shown and described.

DESCRIPTION

FIG. 1 is a perspective view of footwear showing our new design;

FIG. 2 is a right side view thereof;

FIG. 3 is a left side view thereof;

FIG. 4 is a top view thereof;

FIG. 5 is a bottom view thereof;

FIG. 6 is a front view thereof;

FIG. 7 is a rear view thereof;

FIG. 8 is a perspective view of another embodiment of the footwear of FIG. 1;

FIG. 9 is a right side view of FIG. 8;

FIG. 10 is a left side view of FIG. 8;

FIG. 11 is a top view of FIG. 8;

FIG. 12 is a bottom view of FIG. 8;

FIG. 13 is a front view of FIG. 8; and,

FIG. 14 is a rear view of FIG. 8.
